(57) **CLAIM**

The ornamental design for a holder, as shown and described.

DESCRIPTION

FIG. 1 is a top front isometric view of a holder in accordance with the new design;

FIG. 2 is a front elevational view thereof, a rear elevational view being a mirror image thereof;

FIG. 3 is a right side elevational view thereof, a left side elevational view being a mirror image thereof;

FIG. 4 is a top plan view thereof; and

FIG. 5 is a bottom plan view thereof.

FIG. 6 is a top front isometric view of the holder of FIG. 1;

FIG. 7 is a right side elevational view thereof, a left side elevational view being a mirror image thereof; and

FIG. 8 is a front elevational view thereof, a rear elevational view being a mirror image thereof.

FIG. 9 is a top front isometric view of the holder of FIG. 1;

FIG. 10 is a front elevational view thereof, a rear elevational view being a mirror image thereof; and,

FIG. 11 is a right side elevational view thereof, a left side elevational view being a mirror image thereof.

The broken lines shown in FIGS. 1, 4, 6, 8, 9, 10, and 11 are for the purpose of illustrating portions of the holder that form no part of the claimed design.

1 Claim, 4 Drawing Sheets
